(No Model.)

D. D. HARDY

ORBITAL ROTARY ENGINE.

No. 258,534.

Patented May 23, 1882.

Inventor,
Dexter D. Hatch.
per Almon B. Upsham,
Attorney in fact.

UNITED STATES PATENT OFFICE.

DEXTER D. HARDY, OF HAVANA, ILLINOIS.

ORBITAL ROTARY ENGINE.

SPECIFICATION forming part of Letters Patent No. 258,534, dated May 23, 1882.

Application filed August 20, 1881. (No model.)

To all whom it may concern:

Be it known that I, DEXTER D. HARDY, of Havana, in the county of Mason, in the State of Illinois, have invented an Improved Orbital 5 Rotary Engine; and I do hereby declare that the following is a full, clear, and exact description thereof, reference being had to the annexed drawings, making a part of this specification, in which like letters of reference refer to like 10 parts, and in which—

Figure 1 represents sectional elevation at x ; Fig. 2, a section through the center; Fig. 3, a section at y ; Figs. 4 and 5, explanatory details.

15 The cogs on the inside of the cylinder B are cut all to the same size to fit the spur-wheel A, and the lugs T fastened in place afterward. The extreme diameter of the spur-wheel A is made two-thirds of the diameter of the cylinder B, measuring to the base of the cogs. The 20 lugs T are in height one-third the radius of this cylinder B, and are placed at equal distances apart within said cylinder B, as shown in Fig. 1. Said lugs T are held in place by being made dove-tailing in shape, to fit the place between the two teeth where it is wanted—that is, planed to receive it. Screws are also put in to hold them in place. The faces of 25 these lugs are grooved out and provided with 30 steel tongues J, pressed outward by springs S, for packing, said tongues being held from dropping out by small pins. (Not shown in the drawings.)

The crescent C, which is bolted at its ends 35 to the disk D D', is made to fit between the spur-wheel A and the faces of the lugs T, and is provided on its inside surface with a packing, the same as are the lugs T. In the spur-wheel A are made two recesses, opposite each 40 other, to receive the lugs T as said wheel A passes around on the inside surface of the cylinder B. The crank-pin Z, upon which said spur-wheel A revolves, is fastened at its ends to the disks D and D', said disk D being keyed 45 to the shaft G, by which motion is communicated. The disk D' is attached to the short shaft Z', which operates the valve V. Said shaft Z' has a hole drilled into its end to admit the small rod U, and a slot cut through it 50 near said end to allow the pin R to slide in said slot toward and from the disk D'. This

pin R is attached to the small rod U in such a way as to revolve easily thereon, said rod U being operated by the lever L.

The head H of the cylinder B has three ports 55 cast in it at equal distances apart. The ends of these ports that open into the steam-chest M are made of the shape shown in Fig. 3. Between these ports P there is sunk in the face of the head H an annular groove, 2, concentric with the shaft Z'. From this groove 2 there extends an opening, E, through to the side of said head H, where the exhaust-pipe can be attached. The eccentric F can rotate upon the shaft Z', except as it is held by the 60 pin R, and has a collar extending along said shaft Z', in which is cut a slot shaped as in Fig. 4, the two arms of which run lengthwise in said eccentric-collar F, but in opposite directions, and are joined by a long slot running 65 half-way around in the circumference of said collar. By this construction, when the pin R is pushed down into one arm of said slot the eccentric F is at an angle of one hundred and eighty degrees to its position when the pin R 70 is in the other arm of said slot. The valve V 75 revolves upon this eccentric F, being held against the head H by a small shoulder on said eccentric and having sunk in its face the annular groove 1 concentric with it. 80

The operation of this engine is as follows: Steam being let into the chest M through a pipe at E', at once fills the upper and right-hand chambers at P and P' through the ports P and P', which are, as shown in Fig. 3, each half 85 open. The other port, P², is, however, open to the exhaust-pipe, as shown in Fig. 2, as the air or steam can there pass from the port P² through the annular groove 1 into the groove 2 and from thence into the opening E. The 90 steam in the chamber at P now does no work, though after the first revolution this represents steam that has just performed its work. These three conditions of pressure about the wheel A cause said wheel A to be carried toward the left, pushing with it the crank-pin Z, and causing thereby the disks D and D' to rotate, taking around with them the crescent C. Soon as this crescent C touches the lower lug T this chamber at P' ceases to do any more 95 work and becomes as was the chamber at P. In the meantime the valve V has changed po-

sition, so that P^2 is now taking in steam and P is exhaust. The pressure from P^2 now pushes the wheel A upward till P takes it, and P' becomes exhaust, and so on around again. The 5 shaft Z' communicates motion through the pin R to the collar and eccentric F, and thence to the valve V.

To reverse this engine, taking it as shown in Fig. 2, the pin R is drawn by the rod U and 10 lever L up out of the lower arm of the double-armed slot in the eccentric-collar F. The pressure of the steam holds the eccentric F stationary, but the shaft Z' continues to revolve for half a turn from the momentum of the engine. 15 This brings said pin to the other arm of said slot, into which it is at once drawn by a further pressure on the lever L. This makes an exactly-opposite position of the eccentric and valve V—what being before an exhaust-port 20 now taking steam, and the engine accordingly begins rotating in the other direction.

What I claim as my invention, and for which I desire Letters Patent, is as follows, to wit:

1. As a valve for rotary engines, the rod U, 25 swiveled to the pin R, the eccentric F, having a slotted collar, the valve V, having upon one

side an annular groove, and the slotted shaft Z', rotated by the disk D', in combination with the head H, having ports P and an annular groove with a discharge-pipe leading there- 30 from, as set forth.

2. The combination of the stationary internally-toothed cylinder B, having two or more lugs, T, the heads H' and H, having ports P and fastened to said cylinder B, the spur-gear 35 wheel A, having recesses to admit said lugs T, the crescent C, and disks D' and D, bolted to said crescent C, with shaft G and crank-pin Z, as and for the purpose specified.

3. The rod U, pin R, eccentric F, valve V, 40 shaft Z', and disk D', in combination with the head H, having ports P, head H', disk D, internally-toothed cylinder B, crescent C, spur-wheel A, and crank-pin Z, as and for the purpose specified.

In testimony that I claim the foregoing invention, I have hereunto set my hand this 17th day of August, 1881.

DEXTER D. HARDY.
